Charles E. Wing, East Lansing, Mich., assignor to General Motors Corporation, Detroit, Mich., a corporation of Delaware

Application April 23, 1956, Serial No. 579,807

1 Claim. (Cl. 261—43)

The present invention relates to an improved fuel reservoir venting mechanism for a carburetor. The present invention more specifically relates to an improvement which makes cold starting easier with carburetors utilizing atmospherically vented fuel bowls.

In order to reduce hot starting problems, carburetors are frequently provided with fuel bowl venting mechanisms permitting the fuel vapors which form in the fuel bowl when an engine stops hot to pass to the atmosphere. Such venting mechanisms are shown in copending applications Serial No. 264,136 Olson et al. filed December 29, 1951 and Serial No. 579,806, filed April 23, 1956 Olson. While these mechanisms do greatly reduce hot starting problems, it has been found that under certain atmospheric conditions that a cold starting problem arises which the present invention seeks to alleviate.

With the fuel reservoir vent open, as is the case with the engine stopped, and further with the vehicle facing into a wind, it has been found that over a period of time the fuel in the reservoir will be evaporated through the fuel bowl vent to such an extent that cold starting of the engine becomes rather difficult.

It has been found that where the ambient air blows over the vent mechanism over a period of time, as might occur when a car was parked outside over-night, the fuel level in the bowl will be reduced to such an extent that the engine cranking time is perceptibly increased, e. g., to 9-12 seconds, until the fuel bowl level is sufficiently raised to supply an adequate starting charge. This situation is particularly aggravated in cold weather when very rich starting mixtures are necessary.

It has been found that the evaporation of fuel from the reservoir is greatly accelerated as the velocity of the ambient air passing over the vent mechanism increases. It is theorized that the increased rate of evaporation is due to an aspirating action created by the air flowing rapidly over the reservoir vent. The aspirating action tends to reduce the pressure within the reservoir below atmospheric which, of course, accelerates the rate of surface evaporation.

Accordingly, it is a primary purpose of the present invention to reduce the evaporation of fuel when the fuel bowl or reservoir is vented to atmosphere. Pursuant to this purpose a device has been developed which in conjunction with venting mechanisms insures that the reservoir will be maintained at least at atmospheric pressure even when the ambient air is moving at a considerable velocity over the vent mechanism.

A preferred form of the mechanism by which the above purpose is achieved is shown in accompanying drawings and will hereinafter be described in detail.

In the drawings:

Figure 1 is a partially sectioned elevational view of a carburetor embodying the subject invention.

Figure 2 is a fragmentary plan view of Figure 1.

2

Figure 3 is a fragmentary enlargement of the vent mechanism embodying the subject invention.

Referring to Figure 1, a carburetor is shown generally at 10 and includes a fuel bowl or reservoir casing 12, a throttle body 14 and a reservoir cover 16. Mounted on a shaft 18 in the throttle body is a throttle valve 20, shown in a substantially closed position. Also fixed to the throttle shaft 18 is a lever 22 articulated at one end to a throttle pedal controlled rod 24. Likewise fixed to the throttle shaft 18 is another lever 26 and adapted to rotate therewith a control link 28.

As already referred to above, it has been found desirable to provide a reservoir venting mechanism which opens the reservoir to atmosphere when the throttle valve is in a closed or substantially closed position, the purpose of this type of vent being generally to maintain the float bowl reservoir at atmospheric pressure which facilitates starting a hot engine. To this end, the fuel reservoir cover 16 is provided with an upstanding hollow vent casing 30 which communicates at its lower end with the upper or fuel free portion of the fuel reservoir. The vent casing 30 is formed with horizontally aligned openings 32 and 34 therethrough. Opening 34 has securely fitted therein an apertured cover 36 which is adapted to slidably support a valve member 38. The valve member 38 includes a stem 40 slidably supported in the cover 36 and a valve head 42 adapted to seat against and close opening 32 in the vent casing 30. A seat or retainer member 44 is mounted on the end of valve stem 40 exteriorly to the vent casing 30 and is adapted to support one end of a spring 46, the other end of which spring biases against cover 36 and thereby urges the valve stem and head to the left, as viewed in Figure 1, to close port 32.

In order to open valve 38 by moving valve head 42 away from the vent port 32, a lever 50 is centrally pivotably mounted on the fuel reservoir casing 16 through a stud 51. Lever 50 includes a pair of arms 52 and 54. The arm 54 is adapted to engage with valve stem 40 and upon rotation of the lever 50 control the movement of vent valve 38. Arm 52 of lever 50 is articulated to the other end of throttle control link 28.

An impact valve 60 is provided for the purpose of preventing liquid fuel from splashing out of the venting mechanism and is specifically described and claimed in copending application Serial No. 579,806, filed April 23, 1956 Olson.

In the vent mechanism as thus far described it will be seen that with the throttle valve 20 closed or substantially closed, the vent valve 38 is held in an open position thereby communicating the fuel reservoir to atmosphere. This will be the condition of the vent mechanism whenever the throttle valve is in an idling or closed position as will be the case when the vehicle is stopped and the carburetor inoperative. As already noted, it is under this condition, as when the vehicle is parked over a reasonably long period of time, that excessive fuel bowl evaporation will take place particularly when the ambient air is moving over the carburetor at above normal velocities.

While the subject invention is not limited to a precise type of fuel reservoir venting mechanism, for illustrative purposes it has been shown in combination with a venting mechanism of the general type shown and described in copending applications Serial No. 264,136 Olson et al. filed December 29, 1951 and Serial No. 579,806, filed April 23, 1956 Olson. As shown in Figure 1, the front of the carburetor is to the left and the ambient air flowing over the carburetor normally flows from the left to the right. Under these conditions, and unless otherwise corrected, it will be seen that the air in so flowing over the vent mechanism would tend to flow past the rearwardly facing vent port 32 and

thereby reduce the pressure within the fuel reservoir below atmospheric and thus facilitate the surface evaporation of fuel within the reservoir. To avoid the occurrence of this phenomenon a shield 70 is mounted in any convenient manner upon the reservoir cover 16 so as to partially cover the vent casing 30.

The shield 70 is of a sufficient size to permit the vent valve 38 to open. It will also be noted that in this embodiment of the invention, the opened end 72 of the cup-shaped shield 70 faces in an up-wind direction with respect to the normal air flow past the carburetor. In this respect the shield 70 opens in the opposite direction relative to vent port 32. This relationship between the shield and the vent port 32 has been found to eliminate the aspirating action otherwise occasioned by the rapid flow of air over the vent mechanism. With this arrangement of the shield a static air pressure head will be built up in the space confined between the shield and the vent mechanism 30 which will insure the pressure in the float bowl being at least atmospheric. It is even likely that this static pressure head created by the ram-velocity effect of rapidly flowing ambient air would be slightly super atmospheric which would, of course, greatly reduce the surface evaporation of fuel from the fuel reservoir.

While the arrangement of the shield 70 with respect to the vent casing 30 is preferred with the particular carburetor used for illustrative purposes, it is to be understood that the shield function may be achieved with various other structural arrangements. The important relationship between the cover or shield and the associated vent mechanism is that they be oriented with respect to air

flow so as to avoid any aspirating action relative to the fuel bowl and even more preferably that the arrangement insure an atmospheric or super atmospheric static pressure head within the fuel bowl reservoir.

I claim:

A carburetor comprising a throttle valve, a fuel reservoir casing, a cover for said casing, a vent casing disposed on said cover and in communication with said fuel reservoir, a port in said vent casing open to atmosphere, a vent valve normally closing said port, and means connecting said throttle and vent valves permitting said vent valve to open when said throttle valve is in a substantially closed position, and a cup-shaped shield mounted on said cover and partially surrounding said vent casing, said port opening downwind and said shield opening upwind with respect to the direction in which ambient air normally passes over said carburetor, said vent valve opening toward the closed end of said shield.
